UNITED STATES PATENT OFFICE.

AMOS J. SCRITCHFIELD, OF WENDELL, IDAHO.

STOVEPIPE CONNECTION.

1,232,436.

Specification of Letters Patent. Patented July 3, 1917.

Application filed February 2, 1917. Serial No. 146,149.

To all whom it may concern:

Be it known that I, AMOS J. SCRITCHFIELD, a citizen of the United States, residing at Wendell, in the county of Gooding and State of Idaho, have invented certain new and useful Improvements in Stovepipe Connections; and I do hereby declare the following to be a full, clear, and exact description of the invention, such as will enable others skilled in the art to which it appertains to make and use the same.

This invention relates to a stove pipe connection and has for one of its objects the provision of a device of this character especially adapted to lock a pair of sections of a stove pipe together and which will prevent either of the sections from turning in relation to each other.

Another object of this invention is to provide a locking lever pivoted to one section and adapted to engage notches in the other section to prevent the sections from pulling apart or separating.

A further object of this invention is the provision of an inwardly directed lug formed upon one section and adapted to engage the ridge of the other section and which cooperates with the locking lever in locking the pair of sections together, thus preventing either of the sections from turning in relation to each other.

A still further object of this invention is the provision of a stove pipe connection of the above stated character, which shall be simple, durable and efficient, and which may be manufactured and sold at a comparatively low cost.

With these and other objects in view, as will become more apparent as the description proceeds, the invention consists of certain novel features of construction, combination and arrangement of parts as will be hereinafter more fully described and claimed.

For a complete understanding of my invention, reference will be had to the following description and accompanying drawing, in which:

Figure 1 is a side elevation of a stove pipe connection constructed in accordance with my invention, illustrating the locking lever in an unlocked position.

Fig. 2 is a similar view illustrating the locking lever in a locked position.

Fig. 3 is a horizontal sectional view taken on the line 3—3 of Fig. 1.

Fig. 4 is a detail sectional view taken on the line 4—4 of Fig. 1.

Fig. 5 is a detail perspective view of the locking lever.

Referring in detail to the drawing, the numeral 1 indicates the female section and 2 the male section of a stove pipe. The section 2 has the usual ridge 3 formed by taking each edge of the section and interlocking it as clearly illustrated in Fig. 4. The ridge 3 is provided with a plurality of vertically arranged V-shaped recesses 4.

An inwardly directed tongue 5 is riveted or otherwise secured to the section 1 and when the sections are assembled or placed together, the inwardly directed tongue 5 engages one edge of the ridge 3 and locks the sections against turning movement in relation to each other in one direction. Pivot-ed to the section 1 adjacent the inwardly directed tongue 5 is a locking lever 6 pivot-ed at 7 and has its lower end enlarged to form a dog 8 for engagement with any one of the V-shaped recesses 4 of the section 2. 80 A flexible extension 9 is formed upon the upper end of the lever 6 and is constructed of resilient metal and is adapted to ride over a lug 10 secured to the section 1 when the locking lever is moved into operative or locking position as illustrated in Fig. 2 to cause the dog to be received within one of the V-shaped recesses 4. When in this position, the flexible extension 9 passes over the lug 10 and under the same to prevent the lever from being moved from an operative or locking position.

From the foregoing description taken in connection with the accompanying drawing, it will be noted that the locking lever 6 will hold the sections 1 and 2 against turning movement in relation to each other in one direction, while the inwardly directed tongue 5 will prevent the sections from turning in the opposite direction in relation to each other.

While I have shown and described the preferred embodiment of my invention, it will be understood that minor changes in construction, combination and arrangement of parts may be made without departing from the spirit and scope of the invention as claimed.

Having thus described my invention, what I claim is:

1. A stove pipe connection comprising male and female sections, said male section

having a ridge provided with a plurality of V-shaped recesses, a locking lever pivoted to the female section and adapted to engage either of the V-shaped recesses, a flexible extension formed on said lever, and a lug formed on the female section and adapted to be engaged by the flexible extension to hold the lever in operative position.

2. A stove pipe connection comprising 10 male and female sections, said female section having notches therein, a locking lever pivoted to said female section and adapted to engage either of the notches, means holding the lever against movement to lock 15 the sections against separation and rotation and against turning movement with relation to each other in one direction, and a tongue upon the female section and adapted to engage a portion of the male section to 20 lock the sections against turning movement

with relation to each other in the other direction.

3. A stove pipe connection comprising male and female sections, said male section having a ridge provided with a plurality of V-shaped recesses, a locking lever pivoted to the female section and adapted to engage either of the recesses, means for holding the lever in operative position, and an inwardly disposed tongue formed on the female section and adapted to engage the ridge to lock the sections against turning movement in one direction in relation to each other. 25

In testimony whereof I affix my signature in presence of two witnesses.

AMOS J. SCRITCHFIELD.
